BED LEG

Clem B. Colson, Los Angeles, Calif.

Application January 27, 1949, Serial No. 521

Term of patent 7 years

(Cl. D5—2)

To all whom it may concern:

Be it known that I, Clem B. Colson, a citizen of the United States of America and a resident of Los Angeles, county of Los Angeles, State of California, have invented a new, original, and ornamental Design for a Bed Leg, of which the following is a specification, reference being had to and including the drawing as forming a part thereof.

In the drawing:

Figure 1 is a front elevational view of a bed leg, showing my new design; and,

Figure 2 is a top-plan view thereof; while,

Figure 3 is a rear elevational view of the article.

Figure 4 is a side elevational view of the same.

I claim:

The ornamental design for a bed leg, as shown.

CLEM B. COLSON.
